NIPPLE FOR NURSING BOTTLES

Louis Garfield, New York, N. Y.

Application October 21, 1936, Serial No. 106,733

1 Claim. (Cl. 128—252)

This invention relates to nipples, and more particularly has for its object to provide a novel means of permitting air to enter the interior of the nipple while the nipple is being used, and the second object is to provide a secure hold of the nipple on the bottle, and the third object is to provide a tab which permits a quick and convenient means of removing the nipple from the bottle.

10 The invention consists of improved means for providing a supply of air into the interior of the nipple while it is being used, and also consists in providing an improved means for holding the nipple securely to the bottle, and finally provides 15 means in the form of a tab which extends along the length of the bottle and may be readily gripped so as to conveniently and quickly remove the nipple from the bottle.

Other features of the invention will be herein- 20 after described and pointed out, and an embodiment of the invention will be shown in the accompanying drawing and described in the following description, and the invention will be finally pointed out in the appended claim.

25 In the accompanying drawing

Figure 1 is a perspective view partially in section showing my improved nipple applied to the end of a bottle,

Figure 2 is an enlarged sectional longitudinal 30 view of my improved nipple taken on line 2—2 of Figure 1,

Figure 3 is a longitudinal section taken on line 3—3 of Figure 2,

Figure 4 is a bottom view of Figure 2,

35 Figure 5 is a cross section taken on line 5—5 of Figure 2, and

Figure 6 is a cross section of a bottle taken on line 6—6 of Figure 2.

Similar characters of reference indicate corre- 40 sponding parts throughout the various views.

Referring to the drawing, and more particu- 45 larly to Figures 1 and 2, the bottle 10 is provided with a collar 11 which is disposed somewhat spaced from the uppermost edge 12 of the bottle. In order to obtain a secure hold of the nipple 50 upon the bottle, these bottles being of a standard make, the nipple is provided with a circumferential recess 14 and is provided with a shoulder portion 15 adapted to engage the lower surface 55 of the collar 11. Another shoulder portion 16 is provided, adapted to engage the uppermost surface of the collar 11. By thus providing this recess 14 with the shoulders 15 and 16 and making the nipple so that the size of this recess is smaller than the size of the collar 11, it is neces-

sary to expand the rubber of the nipple, and by the forces acting to contract the nipple to its initial state the nipple is securely held to the collar 11 when the nipple has been applied to the bottle.

Along the length of one side 20 of the nipple a tab 21 is provided which has its exterior surface 22 in alignment with the surface 20, but the inner surface 23 is curved so as to have substantially the contour of the bottle. This 10 curvature permits the innermost part of the tab to abut the bottle, and at the same time the sides of the tab, looked at in the bottom view of Figure 4, are inclined, as shown by the surfaces 26, and the combination of these parts of extending the tab 21 in alignment with the nipple to the exterior surface of the nipple, curving it at the inner surface, and inclining the sides 26, enables a tab to be produced which may be readily gripped by the hand so as to pull the nipple 20 off the bottle. Without a tab it is difficult to grip the lowermost part of the nipple since it is under tension, and this tab permits the nipple to be readily gripped and removed from the bottle.

A further portion of the invention consists in providing one wall of the nipple with a channel 30 which terminates near the curved shoulder 31 of the nipple. The nipple portion is made wider than the ordinary nipple so as to provide a way to allow for the channel 30. The channel 30 is on one side of the recess 14, there being a wall 32 between the recess 14 and the channel 30. The uppermost end of this channel 30 is encountered by a very thin wall of the nipple structure indicated by 33, and when molding these nipples the extreme end of the molding pin which forms the channel 30 does not pierce this wall 33 but allows this wall 33 to be conformed. This wall 33 is 30 of semi-circular shape as seen in Figure 3 and extends over the uppermost edge of the channel 30. The nipple is particularly formed to provide this wall 33. After the nipple has been molded and vulcanized and is ready for use, a rod is 35 inserted in the channel 30 and pushed upwardly into the channel 30 until the free end of the rod abuts against this wall 33. The rod is then further moved until the wall 33 is pierced and then the rod is immediately withdrawn. This wall 33 40 is very thin, and after it has been pierced the parts of the wall, due to their own inherent resiliency, again abut each other along the ruptured portion so that to the naked eye one would 45 only see a very faint line of a relatively small 50 55

length. The flexibility of this thin wall permits, however, these ruptured portions to act as a valve when air is sucked in through the channel 30, and again when the sucking action immediately 5 stops, the inherent resiliency of the material forming the wall 33 causes the ruptured portions to go back again into their abutting position. Thus, by sucking in air through the channel 30 the ruptured portions are separated, and by stop- 10 ping the suction the ruptured portions again go back into their former position.

It will be particularly noted that the wall 33 is directly above the shoulder 38 and is, in a sense, in a protected position in that the fluid passes 15 out of the interior of the neck of the bottle directly through the nipple towards its opening 39 and the shoulder 38, in a sense, prevents this fluid from going against the valve 33, the air supply, however, being readily permitted in accordance 20 with the manner described heretofore.

It will be seen from the foregoing that this invention embodied in the improved nipple consists of three essential parts; first, a means for securely holding the nipple to the bottle due to 25 the pressure of the material forming the nipple against the collar of the bottle on all sides of the collar; secondly, the provision of a tab adapted to extend along the longitudinal length of the bottle and having a curved inner surface to con- 30 form to the contour of the bottle, whereby the nipple may be readily removed; and, finally, means are provided in a thickened wall of the nipple to provide an air channel which terminates in a bleed valve or a valve formed from a ruptured

portion of the membrane or wall in line with the innermost end of the air channel.

Having thus described the embodiment of my invention and the various features thereof, I do not wish to be limited to the particular details 5 thereof as shown and described, since changes may be made therein without departing from the spirit of my invention as defined in the accompanying claim.

What is claimed is:

In a nipple, the combination of two interiorly disposed collars having a recess therebetween adapted to engage the collar of a bottle, an enlarged wall at one circumferential portion of the nipple, said wall having a straight channel in the 15 enlarged portion perpendicular to the plane passing through the collar, and a membrane at the innermost end of the channel bridging the same and in line with the uppermost interior collar, said membrane being integral and adapted to 20 act as a valve for the inlet of air from the exterior of the nipple to the interior thereof, and a tab integral with said nipple disposed diametrically opposite to the enlarged wall, the outer surface of the tab being in line with the outer surface of 25 the nipple, the inner surface of the tab being curved to conform to the curved shape of the feeding bottle, said tab having lateral walls substantially radial to the nipple, whereby the tab being disposed diametrically opposite to the enlarged wall enables a quick removal of the nipple from the bottle by the enlarged wall acting as a fulcrum.

LOUIS GARFIELD.
